UNITED STATES PATENT OFFICE.

JAMES F. GOODRIDGE, OF NEW YORK, N. Y., ASSIGNOR TO SAMUEL MAY, JR., OF BOSTON, MASSACHUSETTS.

NON-REFILLABLE BOTTLE.

1,179,715.

Specification of Letters Patent. Patented Apr. 18, 1916.

Application filed April 7, 1915. Serial No. 19,643.

To all whom it may concern:

Be it known that I, JAMES F. GOODRIDGE, a citizen of the United States, and a resident of the borough of Manhattan, city, county, and State of New York, have invented an Improvement in Non-Refillable Bottles, of which the following description, in connection with the accompanying drawings, is a specification, like letters on the drawings representing like parts.

The present invention relates to an improved device for preventing the unauthorized refilling of liquid containers; the term non-refillable bottle being generally used 15 to describe a container so equipped.

The invention has for its object the simplification of known structures which have been heretofore used to accomplish the same purpose, and the provision of means which 20 will most effectively accomplish the purposes in view, but which will nevertheless, be simple in construction, inexpensive to manufacture, and with which a bottle may be easily equipped to make it impossible to 25 refill the same without destroying and removing the entire device.

In the accompanying drawings, one embodiment of this invention is shown, and therein—

30 Figure 1 is a vertical section of the improved device, inverted and in pouring position; the line of the section in this and all similar sections being taken slightly forward of the central vertical plane; Fig. 2 is a 35 vertical section corresponding to Fig. 1, showing the device upright with the valve closed; Fig. 3 is a horizontal section on the line 3—3 of Fig. 1, the valve member having been turned slightly for clearness in showing other parts.

The general objects to be attained by the provision of such means as are herein described for use in connection with liquid containers of all kinds, are well known and 45 need not be here set forth at length. It may well be pointed out, however, that a device to be successful must be extremely simple in construction and be capable of manufacture at small cost without sacrificing its effectiveness in accomplishing the desired 50 purposes. A large number of non-refillable bottles have been invented, but few have gone into general use because of the excessive cost of manufacture. It matters little 55 whether a device be efficient or not if the

use thereof necessitates an outlay disproportionate to the value of the protection afforded thereby. It is sought, in the present case, to provide a non-refillable bottle which will combine the effectiveness of the 60 more complicated and expensive structures with simplicity of construction and inexpensiveness of manufacture; in short, to make a distinctly practical device having a reasonable protective value. 65

Referring to the accompanying drawings, a bottle neck *a* is shown as provided with an interiorly projecting shoulder *b*. To this shoulder a washer *c* is fitted which forms a valve seat and separates the valve 70 chamber from the interior of the bottle. The valve seat *c* may be, and preferably is cemented to the shoulder *a*, and has a centrally located passage therethrough which, in the present instance has a diameter approximately one-third the diameter of the valve seat, thus leaving a relatively large seating area for the valve. A valve *d* is loosely fitted within the valve chamber, which is formed entirely within the bottle 75 neck, the valve having a limited movement therein toward and away from the valve seat. This valve is provided with a conical surface *d'* to engage a corresponding surface *c'* of the valve seat thus securing a reasonably tight closure because of the relatively large seating area. The valve is also provided with radial lugs *e* which extend to the walls of the valve chamber formed by the bottle neck and position the valve within 80 the valve chamber to insure its proper seating and to allow a space for the liquid to pass by the valve when the same is open. It is desirable to have the valve as light as 85 possible in order that the least flow of liquid past the same in either direction will move the valve to open or close it as the case may be. This is particularly desirable to frustrate any attempt to refill the bottle. With 90 this in view, the valve is hollowed out on what appears as its under side in Fig. 1, the concave recess being indicated by *f*.

A cap *g* forming the outlet is fitted into the end of the bottle neck and cemented thereto. It is provided with a flange *h* which bears against the end of the wall of the bottle neck and correctly positions the cap *g* in relation to the other parts of the device. The cap thus forms the end wall 105 of the valve chamber. Lugs *i* are formed 110

integrally with the cap and constitute means for limiting the movement of the valve mechanism.

In the present structure, the liquid flowing past the valve *d* is not relied upon as the sole means of operating this valve to close the same and prevent the refilling of the bottle; but in addition thereto, there may be provided a weight to act upon the valve to close it when the bottle is held in any other than an approximately inverted position. The means referred to are herein shown as a ball *j* which is loosely retained in its proper place within the cavity *f* of the valve seat by the lugs *i* upon the cap *g*. It will at once be apparent that when the bottle is held in an approximately horizontal position, at least part of the weight of the ball will be thrown against the valve *d* and tend to force the valve into contact with its seat *c*, whereby any attempt to refill the bottle when in this position will prove unsuccessful. When the bottle is held in a position for pouring, the valve will open and the liquid contents of the bottle will flow through the aperture in the valve seat *c*, past the valve *d*, between the lugs *e*, thence between the lugs *i* and so out of the aperture in the cap *g*. The air will pass in through corresponding spaces above the valve.

The cross-section in Fig. 3 shows the construction of the valve with its positioning lugs *e*, in its relation to the ball *j* and the ball retaining means. In this figure, the valve has been rotated slightly to the right in order to show the ball retaining lugs *i* upon the cap *g*.

Preferably the various parts of the device herein described are made of porcelain or some such non-corrosive substance which will be unaffected by the contents of the

bottle; but it will, of course, be understood that any suitable material may be used.

I claim as my invention:

In a non-refillable bottle, the combination of a frusto conical valve seat located within the bottle neck and having a pouring opening, a conical headed valve to coöperate with the valve seat to close said opening, means upon the valve to space the same from the side walls of the bottle neck, a ball weight at the discharge side of said valve, a cap closure for the bottle neck having an inner wall sloping toward a restricted pouring opening therein, valve supporting lugs at the said inner wall adapted to support the valve independently of said ball weight, each said lug having a sloping surface to deflect the ball gravitating down it, in a diagonal direction, the valve being supported independently of and free from said ball when the bottle is in pouring position thus permitting the ball to move freely at all times under the action of the flowing liquid between the valve and the said lugs, and permitting the ball in its independent movement relative to said valve to strike the latter with impact, when the bottle is held upright, to force it into engagement with its seat and tend to hold it thereon until it has passed well beyond the horizontal position while being inverted, thereby preventing the refilling of the bottle.

In testimony whereof, I have signed my name to this specification, in the presence of two subscribing witnesses, this third day of April, 1915.

JAMES F. GOODRIDGE.
